UNITED STATES PATENT OFFICE.

AGATHA LOUISSA DAVIS, OF CLINTON, SOUTH CAROLINA.

CIRCUIT-CLOSER

1,100,957.

Specification of Letters Patent. Patented June 23, 1914.

Application filed September 20, 1911. Serial No. 650,375.

To all whom it may concern:

Be it known that I, AGATHA L. DAVIS, a citizen of the United States, and a resident of Clinton, in the county of Laurens and State of South Carolina, have invented a new and Improved Circuit-Closer, of which the following is a full, clear, and exact description.

My invention relates to electrically operated railway gates, and has for its object to provide a circuit closer for controlling the actuating means for the gates. The circuit closers are placed along the railroad tracks a suitable distance on either side of the gates, and are designed to be operated by the wheels of a train to close the circuits in time to energize the actuating devices to lower the gates and temporarily close the crossing before the train which operates the circuit closers passes the point at which the gates are located.

Reference is to be had to the accompanying drawings forming a part of this specification, in which the same characters of reference indicate the same parts in all the views.

Figure 1 is a longitudinal sectional view of a casing or conduit which is placed in position beside the rails, and in which the circuit closers actuated by the wheels of the train are mounted; Fig. 2 is a view similar to Fig. 1, showing a different type of circuit closers; Fig. 3 is a transverse vertical sectional view on the line 3-3 of Fig. 4; Fig. 4 is a view on the line 4-4 of Fig. 3; Fig. 5 is a sectional view similar to that shown in Fig. 3, showing another form of conduit and another form of circuit closer mounted therein; Fig. 6 is a top plan view of the parts shown in Fig. 5; Figs. 7 and 8 are perspective views of other forms of circuit closers similar to those shown on Figs. 4 and 2 respectively; and Fig. 9 shows another form of stop for preventing the circuit closers shown on Figs. 1 and 2, for example, from swinging too much around their supporting pivots.

Referring to Figs. 1, 2, 3 and 4 of the drawing, a plurality of circuit closers 17 or 17' are located in a casing 15 arranged along side of the rail 16, as shown in Figs. 1 to 4. This casing is preferably made of some insulating material, such as wood, but I may make it of metal if desired. A pair of conductors, such as 13 and 13' for example, are laid in the bottom of this casing,

and I form an elongated drain slot 15' in the bottom between the conductors, to prevent the accumulation of water therein, which would short circuit the conductors and cause waste of current. The circuit closers 17 or 17' are mounted in the casing 15 at suitable distances apart, each of the circuit closers being hung on a spindle 18, with the upper ends thereof projecting above the open top of the casing 15, in position to be engaged and tilted by the wheels of a passing train. In Fig. 1 the circuit closers 17 have curved lower faces 19 and when tilted their lower faces come in contact with the conductors 13 and 13', to close the circuit and operate the gates. The circuit closers 17 or 17' will be used in suitable number, and they will be spaced apart at such intervals that one or more of them will always be engaged by the train wheels, to close the circuit. After the train has passed, the circuit closers will return to their original position, breaking the circuit and allowing the gates to rise.

In order to keep the circuit closers from vibrating, or moving too freely around their pivots 18, I prefer to use stops 22, mounted in slots 21 in the side of the casing 15. These stops are preferably connected by a spring 23, to dampen the swinging movements of the circuit closers 17, and bring them to rest.

The circuit closers 17 are preferably made of vanadium steel, or some other good conducting substance, and they are made narrow at the top 20, where they are engaged by the wheels of the train, and broad at the bottom. The forward side thereof is longer than the rear side, so that these circuit closers will only become operative to lower the gates at the crossings when they are engaged by a train passing in the direction of the arrows shown in Fig. 1. When engaged by a train in the opposite direction they will be tilted; but on account of their short sides being lowered in this instance, the bottom 19 will not come into contact with the conductors in the bottom of the casing. This form of circuit closer is used for crossings along the main line, and it is placed along both tracks on each side of the gates, in such positions that the actuating means for the gates will be operated whenever a train passes, no matter in what direction it may be going, or on which track it may be passing.

The circuit closer 17' shown in Figs. 2 and 4 is more regular in shape, having the front and rear sides of about the same dimensions. This form of circuit closer is to be employed at switch points and in yards where there is a good deal of shifting to be done, and where there are plenty of trains moving in both directions in consequence. This form of circuit closer will operate to close the circuit to the gates when tilted in either direction; whereas the other form will operate to close the circuit when tilted in but one direction.

When the circuit closers 17 are employed, those which are placed along the track on the near side of the crossing will have their smaller sides facing the direction from which the train usually comes; those on the far side of the crossing will be turned the opposite way. As a result, those on the near side of the crossing will be operated to lower the gates; but when the train is once past the crossing and tilts those on the far side thereof, the latter will have no effect, for the reason that the smaller sides will be lowered by the train wheels, and the lower surface 19 will not come in contact with the conductors.

By the employment of circuit closers such as described above, for controlling railroad gates, no watchman need be employed, as all of the apparatus is automatically actuated by the train as soon as the locomotive reaches a point a certain distance away from the crossing. At this point the first of the line of circuit closers will be thrown to close the circuit, to lower the gates, and one or more of the circuit closers will be held down in such circuit-closing position by the wheels of the train until the last car has passed the crossing. The last circuit closer will then follow the rest, swing by means of its own weight into such position as to support the circuit-closing surface 19 near to the ground and out of contact with the main conductors.

I wish to have it particularly understood that the circuit closers of the form shown in Fig. 1 are placed in different positions along each track on both sides of a crossing; that is to say, the circuit closers for a given track will be so placed that their shorter sides will face the direction from which a train usually comes on that track; and the circuit closers for the same track on the opposite side of the crossing will have their shorter sides facing in the opposite direction. In consequence, when a train passes on the track in question, the gates will be operated, should the train be passing in the right direction, or temporarily in the opposite direction.

In the form of conduit shown in Figs. 5 and 6, I employ a trough 15', having only a bottom and one side, and having its bottom so shaped that it will fit against the base of the rail 16' and make the web of the rail

form the other side of the casing or conduit in which the conductors 13 and 13' are laid. This casing or conduit will have the usual outlet openings 25 in the bottom, to drain off moisture which would otherwise short-circuit the conductors. In this conduit, I place the number of circuit closers 27, which are prismatic in form, as shown in Fig. 7, but have their upper edges cut away, as shown at 28. These circuit closers are mounted to swing on pivot pins 18, supported by the rail 16' and the trough 15', and that part of the upper edge of the circuit closer which is not cut away as shown at 28 in Fig. 7, is arranged to project through a notch or recess 26 in the side of the rail or top of the rail, extending as far back as the web thereof, and this projection 28' will be engaged by the wheels of a passing train, to be tilted around the pin 18, as described above in connection with the other figures.

Fig. 8 shows another form of circuit closer indicated by the numeral 27' having its upper edge partly cut away at 28, and having a projection 28', as in the case of the circuit closer shown in Fig. 7. The circuit closer 27 in Fig. 7 is used for the same purpose, and in the same way, along the tracks adjacent the crossing, as the circuit closers 17' shown in Figs. 2 and 4, and the circuit closers 27' are used in the same relations with regard to the tracks near crossings, as the circuit closers 17 shown, for example, in Fig. 1.

Fig. 9 shows another form of stop which I employ to keep the circuit closers from swinging too much on their pivot pins 18. In this figure, the circuit closers are shown as mounted between the beveled ends of strips 29, which are secured along the insides of the conduit 15 in position to engage the sloping sides of the circuit closers 17 and 17' after these circuit closers have been tilted to a certain extent. This arrangement I prefer to use in place of the spring stops 22 shown in Fig. 4 in connection with the circuit closers 17 and 17'.

It will be understood in connection with Figs. 5 to 8 inclusive, that no form of stop is needed, because of the projections 28' on the circuit closers 27 and 27' being received in recesses 26 in the rail, the sides of these recesses thus acting as stops.

Referring further to Figs. 5 to 8 inclusive, it will be understood that the projections 28' passing up through the recesses 26 in the top of the rail 16' will be engaged by the flat portion of the car wheel when the train passes over them, to tilt the circuit closers. The cut-away portions 28 are for the purpose of preventing the flange on the inside of the rim of the wheel from coming in direct contact with the circuit closers.

In the form of trough shown in Fig. 5 I prefer to use a cover extending from the side

15' over as far as the ball or top of the rail, to protect the circuit closers and conductors against the weather.

All of the parts of my improved system 5 are simple, and they can be installed at a comparatively moderate cost, and easily and cheaply operated in practice.

Having thus described my invention, I claim as new and desire to secure by Letters 10 Patent:

1. A circuit closer comprising a body mounted to swing on a pivot, said body being substantially triangular in cross-section, with the apex thereof above the pivot, said 15 body having its upper edge cut away over the greater portion of its length, the remaining edge of the upper portion forming a projection to be engaged by the wheels of a train to tilt the body to close a circuit 20 through a pair of conductors.

2. In an improvement of the kind described, the combination of a rail having in its head a recess extending laterally out through one side thereof, a vertical member 25 spaced from the web of the rail, and a circuit closer comprising a body pivotally mounted between said member and the web of the rail and having a projecting portion extending through the said recess above the top of the 30 rail to be engaged by the wheel of a train and tilted into position to close a circuit through a pair of conductors.

3. In an improvement of the kind described, the combination with a rail having 35 a lateral recess in its head, of a member extending longitudinally and upwardly parallel with the rail and forming therewith a trough, and a circuit closer pivoted to the rail and to the said member and having 40 a portion projecting into the recess of the head of the rail, above the same.

4. In an improvement of the kind described, the combination with a rail having a lateral recess in its head, of approximately 45 right angular members one of the members fitting upon the base of the rail and the other extending upwardly to form with the rail a trough, and a circuit closer pivoted to the web of the rail and to the said 50 vertical member and having a portion projecting into the recess of the rail and above said rail.

5. In an improvement of the kind described, the combination with a rail having 55 in its head a lateral recess, of approximately right angular members, one of the

members being shaped to fit upon the base and provided with an opening therein and the other extending upwardly parallel with the web of the rail and forming with said 60 rail a trough, and a circuit closer having at its ends pivot-pins mounted in the rail and in the said upwardly extending member, said closer having a portion projecting into the lateral recess of the rail and above said 65 rail.

6. In an improvement of the kind described, the combination with a rail having in its head a lateral recess, of approximately 70 right angular members, one of the members fitting on the base of the rail and the other extending up parallel with the rail and forming therewith a trough, conductors in the bottom of the trough, and a circuit closer having at its ends pivot pins mounted 75 in the rail and the said upwardly extending member, said closer being substantially triangular in cross section and having its apex cut away for the greater portion of its length to form a projection extending 80 into the recess of the rail and above said rail.

7. A circuit closer comprising a body mounted to swing on a pivot, said body being substantially triangular in cross-section, 85 with one side shorter than the other side and the apex thereof above the pivot, said body having its upper edge cut away over the greater portion of its length, the remaining edge of the upper portion forming 90 a projection to be engaged by the wheels of a train, to tilt the body to close the circuit to a pair of conductors.

8. In an improvement of the kind described, the combination of a rail having in 95 its head a recess extending laterally out through one side thereof, a trough or conduit at one side of the rail, conductors in the bottom of the trough or conduit, and a member pivotally mounted in the trough or 100 conduit and projecting into the recess of the rail above the same to be engaged by the wheel of a train and tilted to come into contact with the said conductors.

In testimony whereof I have signed my 105 name to this specification in the presence of two subscribing witnesses.

AGATHA LOUISSA DAVIS.
